[57] CLAIM

The ornamental design for a head for a surface-treating machine, substantially as shown and described.

DESCRIPTION

FIG. 1 is a perspective view of a head for a surface-treating machine showing my new design;
FIG. 2 is a front elevational view, the opposite side being the same in appearance as the side shown;
FIG. 3 is a top plan view shown on a slightly smaller scale;
FIG. 4 is a side elevational view shown on a slightly smaller scale, the opposite side being the same in appearance as the side shown; and
FIG. 5 is a bottom plan view thereof.

FIG. 1

FIG. 2

*FIG. 3**FIG. 4**FIG. 5*
